UNITED STATES PATENT OFFICE.

AUGUST ROUSCH, OF PEEKSKILL, NEW YORK.

DOUBLE-REFLECTING LAMP.

1,151,401.

Specification of Letters Patent. Patented Aug. 24, 1915.

Application filed March 6, 1915. Serial No. 12,508.

To all whom it may concern:

Be it known that I, AUGUST ROUSCH, a citizen of the United States, and resident of Peekskill, in the county of Westchester and 5 State of New York, have invented certain new and useful Improvements in Double-Reflecting Lamps, of which the following is a specification.

This invention relates to, particularly, the 10 lighting of license numbers on vehicles, whether on automobiles, or wagons, carriages, &c.; and its object is to combine in one lamp a signal light, and a light to illuminate the license number.

15 The object is attained by the means set forth in this specification and the accompanying drawing, in which letters and numbers are alike in references to the several parts in the different figures.

20 Figure 1 is a transverse section in elevation through the lighting center of the lamp. Fig. 2 is an elevation of the rear of the central portion of the lamp. Fig. 3 is a modification of form from that shown in the 25 other figures. Fig. 4 is a front elevation of the lamp, without the glass in the cone, and with one end of the horizontal reflector shown in section. Fig. 5 is a perspective view of the lamp showing one end of the 30 casing broken away.

In the perspective view, Fig. 5, it will be seen that the lamp consists of a central conical portion *a*, that constitutes a reflector, having at the small end of the cone an electric bulb *f*. The reflector has a glass front 35 *e*. To this reflector is secured a rectangular casing *b* extended upon each side of the cone and somewhat below the cone. Where this casing is attached to the cone, the body of 40 the cone is cut away as at *b'*, so as to constitute one chamber of the interior of the cone and of the casing.

Fig. 1 shows the construction of the cone. Its front edge is formed into a screw *e''*, 45 and a cap *d* screws upon it. The cap is cut away leaving only the threaded portion *e'* and a flange *h*. This cap holds a glass *e* in place. The small end of the cone is extended in tubular form *c*, and within the 50 tube is inserted an electric lamp socket *g*. The lamp socket comprises several parts. A tube constitutes the receptacle for the lamp base *f'*, and is partly filled with an insulation *10*. In the insulation is a fixed 55 metal plug *11*, perforated as at *13* to receive a connecting wire *w*, the wire being held by

a screw *12*. A movable plug *14* is kept thrust forward by a spring *15*. A metallic part *16* in the lamp base makes contact with the movable plug *14*. The outer end of the 60 insulation is shown in Fig. 2, showing that there are two wire connectors. The socket is a well known form of lamp socket upon which no claim is made herein, except that it is suitable for the purpose, but not to the 65 exclusion of any suitable lamp socket.

The front of the casing *b* is at right angles to the horizontal center of the lamp and cone reflector; but the rear side of the casing is at an obtuse angle with the front, forming 70 a chamber wider at the bottom than at the top, and both sides of the casing intercept and throw rays from the lamp downward. The highest point of intersection of the casing with the cone coincides with the 75 horizontal center of the cone, or about that, so that part of the lamp film will project rays of light to the extreme ends and corners of the casing, thus making all parts of the interior of the casing reflective. The 80 base of the cone, from the end of the lamp socket, is finished with a parabolic curved bottom as at *t*.

The open bottom of the casing *b* is provided with a groove *1*, Figs. 1, 4 and 5, for 85 a glass *m*, Figs. 1 and 4, to keep out dust and insects. As shown, slight "kinks", as at *o o* near the edge of the casing, and flanges *i i* afford a groove into which to slide the glass. The casing is made to admit the glass at one end, and a means for 90 keeping it in place is shown in Fig. 4, comprising a screw *r'* fast to the casing, a clamp *n* and a nut *r*, the clamp extending under the glass. The interior of the casing will 95 be provided with suitable reflecting surfaces.

The lamp is shown in Fig. 1 as clamped to a license number plate *5*, and it can be seen how the front of the casing will intercept light from the lamp and reflect it downward upon the number plate, and that the rear wall of the casing will cast downward rays that fall upon it. Also, that the cone and the casing reflect rays at right angles 100 to each other. Thus, when used as a rear light, a red glass in the cone makes of the lamp a rear end danger signal, while at the same time a white light will be thrown upon the number plate. If used as a front light, 105 the glass in the cone would be an uncolored glass. For short journeys a few dry batter-

ies would be sufficient to operate the lamp, for vehicles out for a long period a storage battery could be used, while with a modern automobile equipment it becomes simply an addition to the outfit.

The lamp can be secured in juxtaposition with the number plate in any convenient manner. Figs. 1 and 2 show a clamp 1 secured to the casing and provided with screw holes 3 3 for attaching the clamp to number plate holding brackets, and also with slots 2 2 for a strap fastening. The clamp 4 is held to the casing by means of a screw 7 and nut 6, made with a hook 8 at the top, with the end adapted to be bent upon the plate as at 8' at the bottom.

In Fig. 3 is shown a modification of the form of the horizontal reflector or casing. Instead of rectangular extensions the extensions from the cone have the tops of the casing curved from the points of intersection with the cone to the ends of the casing. Otherwise the casing is the same as shown in the other figures.

An object in extending the rear wall of 25 the casing higher than the front wall where the two join the cone, is to avoid an excessive cutting away of the cone surface.

Having described my invention, what I claim and desire to secure by Letters Patent, is—

The combination in a double reflecting lamp of a conical reflector, a lamp in the small end of the cone, the cone provided with a screw-threaded rim, a glass over the rim 25 with an open end cap screwed on the rim to hold the glass, and an elongated rectangular casing attached to the cone, the space in the casing and in the cone united to form one lighting chamber, the outlet from the 40 elongated casing provided with grooves for a glass, a glass in the said grooves, a clamp for holding the glass in place, and supporting clamps attached to the casing.

AUGUST ROUSCH.
